A. BURNS.
SPARK EXTINGUISHER.
APPLICATION FILED AUG. 18, 1917.

1,264,891.

Patented May 7, 1918:

C. L. Parker

Attorney

UNITED STATES PATENT OFFICE.

AL BURNS, OF SUNSET, IDAHO.

SPARK-EXTINGUISHER.

1,264,891.

Specification of Letters Patent. Patented May 7, 1918.

Application filed August 18, 1917. Serial No. 136,936.

To all whom it may concern:

Be it known that I, AL BURNS, a citizen of the United States, residing at Sunset, in the county of Shoshone and State of Idaho, have invented certain new and useful Improvements in Spark-Extinguishers, of which the following is a specification.

My invention relates to improvements in apparatus for automatically supplying a fire extinguishing chemical, liquid or gaseous, to a smoke stack.

An important object of the invention is to provide apparatus of the above mentioned character, which is adapted for use in connection with a railway locomotive, while in no sense restricted to this use, and automatically thrown into operation, when the throttle lever is opened for supplying steam to the cylinders of the engine.

A further object of the invention is to provide apparatus of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same,

Figure 1 is a side elevation, partly diagrammatic, of apparatus embodying my invention, showing the same applied to a railway locomotive, and,

Fig. 2 is a detail section through the automatic valve structure.

In the drawings, wherein for the purpose of illustration is shown a preferred embodiment of my invention, the numeral 5 designates the boiler of a railway locomotive, provided with a smoke stack 6. The numeral 7 designates the usual steam supply pipe, having communication with the steam dome 8 and the steam chest 10 of the locomotive. The supply pipe 7 is equipped with the usual throttle valve 9, operated by the throttle lever (not shown) in the usual manner. When the steam is supplied into the steam chests 10 the pistons of the engine are operated in the usual manner.

My apparatus comprises a storage tank 11, suitably secured to the boiler 5 and adapted for the reception of a liquid fire-extinguishing chemical, held therein under suitable pressure. I may employ water

charged with carbon dioxid gas, while it is to be understood that any other suitable liquid chemical may be employed. Connected with the tank 11 is an outlet pipe 12 having a needle valve 13 connected therein, adapted for adjustment for controlling the volume of fire extinguishing chemical fed through the pipe 12. The pipe 12 discharges into the interior of the stack 6, preferably near its lower end.

Connected in the pipe 12 is a cross shaped casing 14 of an automatic valve structure. The horizontal portion 15 of this casing is connected in the pipe 12. As more clearly shown in Fig. 2, a reciprocating valve 16 is mounted to reciprocate in the vertical portion 17 of the casing 14, and when in the lowermost position, to completely cover the bore of the horizontal portion 15, thus preventing the escape of the chemical from the tank 11. Rigidly connected with the lower end of the valve 16 is a rod 18, connected with a plunger 19. This plunger is adapted to engage when in the lowermost position, stop members or lugs 20, rigidly secured to the vertical portion 17. The lower end of this vertical portion is connected with a pipe 21, in turn connected with the pipe 7. This pipe 21 has a pressure reducing valve 21' connected therein, whereby a suitable amount of steam will be supplied into the lower end of the vertical portion 17, to act upon the plunger 19 and unseat the valve 16, when the throttle valve 9 is opened.

The upper end of the vertical portion 17 carries a cap 22, preferably having screw-threaded engagement therewith. This cap engages a suitably stiff compression spring 23, contacting with the upper end of the valve 16, to normally retain the same in the lowermost position.

The operation of the apparatus is as follows:

When the engineer starts the engine, the throttle valve 9 is opened in the usual manner, and pressure passes through pipe 7 into the steam chest 10. A suitable amount of this pressure passes from pipe 7 through pipe 21, into the lower end of the vertical portion 17, beneath the plunger 19. This pressure raises the plunger and unseats the valve 16. This movement of the valve 16 uncovers the bore of the horizontal portion 15, allowing the liquid fire-extinguishing chemical under pressure in the tank 11, to escape through the pipe 12, to the stack 6.

This chemical being introduced into the stack serves to extinguish the sparks therein.

While I have shown and described my apparatus as applied to a railway locomotive, such showing is for the purpose of illustration only, and it may be used in connection with any steam generating plant.

It is to be understood that the form of my invention herewith shown and described 10 is to be taken as a preferred example of the same, and that various changes in the shape, size, and arrangement of parts may be resorted to without departing from the spirit of the invention or the scope of the subjoined claims.

Having thus described my invention, I claim:—

1. Apparatus of the character described, comprising a storage tank for holding a fire extinguishing chemical under suitable pressure, an outlet pipe connected with the tank 20

and leading to the stack of the engine, a pressure operated valve connected in the pipe, and a pipe connected with the pressure operated valve and adapted for connection 25 with the steam supply pipe of the engine.

2. In apparatus of the character described, a storage tank for holding a fire extinguishing chemical under suitable pressure, an outlet pipe connected with the tank 30 and leading to the stack of the engine, a valve connected in the outlet pipe, pressure operated means to shift the valve, and a pipe connected with the pressure operated means and adapted for connection with the 35 steam supply pipe of the engine.

In testimony whereof I affix my signature in presence of two witnesses.

AL BURNS.

Witnesses:

ELSIE M. RYAN,
Mrs. ED WHITE.
